UNITED STATES PATENT OFFICE.

ALBERT N. STEPHAN, OF FREEPORT, ILLINOIS.

MEANS FOR SUPPLYING MOISTURE AND AIR TO AUTOMOBILE-ENGINES.

1,187,937.

Specification of Letters Patent. Patented June 20, 1916.

Application filed June 16, 1915. Serial No. 34,482.

To all whom it may concern:

Be it known that I, ALBERT N. STEPHAN, a citizen of the United States, residing at Freeport, in the county of Stephenson and State of Illinois, have invented certain new and useful Improvements in Means for Supplying Moisture and Air to Automobile-Engines, of which the following is a specification.

10 This invention relates to means for supplying water vapor, steam, gasoline, alcohol or other fluids to the combustion chamber of an automobile engine.

The invention is herein shown as embodied in an attachment adapted to introduce such fluids into the intake manifold of the engine, the attachment comprising controlling means arranged to be mounted upon the steering column.

20 In the accompanying drawings, Figure 1 is a diagrammatic view illustrating an apparatus embodying the features of my invention. Fig. 2 is a fragmental sectional view. Fig. 3 is a sectional view taken in 25 the plane of dotted line 3—3 of Fig. 1. Fig. 4 is a section on line 4—4 of Fig. 3. Fig. 5 is a fragmental detail view.

In the drawings, A denotes an automobile engine; B a radiator connected in the usual 30 way to the water jacket of the engine cylinder; B' the ordinary overflow pipe of the radiator; A' the intake manifold of the engine; and C the steering column.

One of the features of my invention consists in supplying water vapor from the 35 overflow pipe B' of the radiator to the intake manifold of the engine. On some automobiles, the overflow pipe is on one side of the center line of the car, and on other cars 40 said pipe is on the opposite side. The intake manifold likewise may be on one side or the other of the engine. In order that the device may be attachable to existing cars of various makes, the connection between the overflow pipe and the intake 45 manifold consists in part of a flexible tube 1 of ample length and a nipple 2, said nipple being pivotally connected to the tube, so that the nipple may be screwed into a suitable 50 opening in the intake manifold whether the latter be at one side or the other of the engine. Pivotally connected with the nipple 2 is a cup 3 adapted to contain any suitable priming or cleaning liquid. In order that 55 the cup 3 may be upright, while the nipple 2 extends in the direction which may be

necessary in a given installation, the cup and the nipple are pivotally connected together, as stated. The means for controlling the entrance of water or other fluid to the manifold is located at the axis of such pivotal connection.

4 denotes a lug on the cup 3, and 5 a lug on the nipple 2. These lugs are transversely apertured to receive a tubular pivot or valve casing 6. Said casing has at one end a shoulder 7 adapted to lie at one side of the lug 5, while the other end of the casing 6 is externally screw-threaded to receive a cap 8. The cap 8 and the shouldered portion of the casing 6 are exteriorly adapted to receive wrenches for use in connecting the parts.

A port 9 connects the interior of the cup 3 with an annular chamber 10 in the lug 4. The bore of the nipple 2 communicates with an annular chamber 11 in the lug 5 through a port 12. The chambers 10 and 11 are in constant communication.

13 is a needle valve that controls the port 9. The interior of the valve casing 6 is arranged to communicate with the chambers 10 and 11 by means of ports 14. To one end of the valve casing 6 is secured one end of the tube 1. To the other end of the tube is fixed a coupling 15 consisting of two branches 16 and 17 extending at a right angle to each other. The tube 1 is fixed to the branch 16. The branch 17 is adapted to be slipped upon the lower end of the overflow pipe B' and be secured in place by a set screw 18. The lower end of the coupling 15 is open, as at 15'.

Within the valve casing 6 is a valve member 19 adapted to close communication between the tube 1 and the valve casing. Any suitable means may be employed to operate the valve member 19. Herein I have shown a flexible rod 20 connected to said valve member and extending to a point within convenient reach of the driver. In the drawings, I have shown the rod 20 as inclosed in a flexible tube 21 which is secured at one end of the cap 8, and is attached to the steering column by means of a clamp 22.

23 is a finger piece fixed to the rod 20.

When starting the engine, the supply of fuel may be obtained from the carburetor (not shown) or from the cup 3. After the engine has been started and the cylinder has become sufficiently warm, water vapor may be admitted to the intake manifold by open-

ing the valve member 19, the suction of the engine causing steam or water vapor escaping from overflow pipe B' to be drawn into the tube 1, air being also drawn into the engine through the opening 15^a.

It will be seen that the carburetor or the engine cannot be flooded with water through any use or misuse of the apparatus, as the opening 15^a at all times affords a means of escape for water or vapor descending in the overflow pipe. The entrance to the branch 16 is at one side of the path which overflow water naturally takes by reason of gravity. When the valve member 19 is seated, no water enters the tube 1. When said valve member is unseated, more or less water vapor mixed with air is drawn into the engine cylinder.

The pivotal connection between the cup 3 and the nipple 2, and the flexibility of the tubes 1 and 21 and the rod 20 permit the apparatus to be applied to existing cars of various makes and sizes.

Although the invention is herein disclosed

as embodied in an attachment for automobile power plants, it is evident that the invention may be constructed as an integral part of an automobile.

I claim as my invention:

An attachment for automobile power plants, comprising a flexible tube, a valve casing connected to one end of said tube, an attaching nipple communicating with said casing, a valve in said casing, means for operating the valve, and a coupling comprising two branches, one of said branches being attached to the other end of said tube, and the other branch being adapted for connection to the lower end of an overflow pipe, said coupling having means for the admission of air and the escape of water.

In testimony whereof, I hereunto set my hand in the presence of two witnesses.

ALBERT N. STEPHAN.

In the presence of—

FRED. R. RICE,

THOMAS S. BOWEN.
